(57) **CLAIM**

The ornamental design for a display screen with graphical user interface, as shown and described.

DESCRIPTION

FIG. 1 is a front view of a display screen with graphical user interface or portion thereof, showing my new design;

FIG. 2 is a rear view thereof;

FIG. 3 is a top view thereof;

FIG. 4 is a bottom view thereof;

FIG. 5 is a right side view thereof;

FIG. 6 is a left side view thereof; and,

FIG. 7 is a front view of a detail of FIG. 1, shown enlarged for ease of illustration.

The outermost broken line double rectangle in FIG. 1 and the broken lines in FIGS. 2-6 are included for the purpose of illustrating environmental subject matter and form no part of the claimed design. The inner broken line rectangle in FIG. 1 showing the display screen, and all other broken lines in FIGS. 1 and 7 showing portions of the graphical user interface, are included for the purpose of illustrating portions of the article and form no part of the claimed design.
